UNITED STATES PATENT OFFICE.

HERBERT H. HEWITT, OF BUFFALO, NEW YORK.

CASTING APPARATUS.

1,203,619.

Specification of Letters Patent.

Patented Nov. 7, 1916.

Application filed February 13, 1912. Serial No. 677,357.

To all whom it may concern:

Be it known that I, HERBERT H. HEWITT, a citizen of the United States, and a resident of the city of Buffalo, in the county of Erie and State of New York, have invented certain new and useful Improvements in Casting Apparatus, of which I do declare the following to be a full, clear, and exact description, reference being had to the accompanying drawings, forming part of this specification.

My present invention has for its object to provide an improved construction of casting apparatus which, while susceptible of use in the casting of a variety of articles, is particularly adapted for the casting of chilled car wheels.

The invention consists in the features of novelty hereinafter described, illustrated in the accompanying drawings and particularly pointed out in the several claims at the end of this specification.

Figure 1 is a view in central vertical section through a casting apparatus embodying my invention. Fig. 2 is a central vertical section taken at right angles to Fig. 1, but showing the parts in the position which they occupy when the molds are completely opened and the finished casting is to be removed. Fig. 3 is a view partly in plan and partly in horizontal section on line 3—3 of Fig. 2. Fig. 4 is a view in horizontal section on line 4—4 of Fig. 2.

Upon a suitable foundation 10 rests the base plate 11 from the four corners of which rise the standards or posts 12. As shown, the lower ends of the standards 12 pass through the base plate and are secured thereto by means of nuts 13 that engage the reduced and threaded lower ends of the standards. The base plate 11 is preferably a casting, the upper face of which is formed with ribs to give it the desired strength and centrally from the base plate rises the cylinder 15 that is by preference formed integral therewith. To the top of the cylinder 15 is bolted the cylinder head 16 through which passes a piston rod 17 that carries at its lower end a suitable piston 18. To the lower end of the cylinder 15 leads a fluid pressure pipe 19 and to the top of the cylinder 15 leads a fluid pressure pipe 20. These fluid pressure pipes 19 and 20 are connected to the casing 21 of the three-way valve with

which communicates a fluid delivery pipe 55 22 and an exhaust pipe 23. The three-way valve within the valve casing 21 is of familiar construction and is provided with a handle 24 whereby it can be conveniently manipulated by the attendant. The chambered boss 25 of the cylinder head serves to receive the packing 26 that is held in place by a gland 27. By reference to Fig. 4 it will be seen that the boss 25 of the cylinder head 16 is formed with six offset portions, three of which are tapped with threaded holes to receive bolts. The flanged portion of the gland 27 is of triangular shape and through this flanged portion of the gland 27 pass threaded bolts 28 that engage correspondingly threaded holes in the boss 25 of the cylinder head 16. Within the remaining holes of the boss 25 are placed stops 30 that are designed by their adjustment to limit with exactness the downward movement of a central support or plunger, as will presently more fully appear. In order to retain the stops 30 in their set position, pointed screws 31 are preferably passed through threaded holes in the side walls of the upstanding portions of the boss 25 opposite the stops 30.

The upper ends of the corner posts or standards 12 pass through the lateral openings in the top plate 40 and are held in secure engagement with the top plate by means of caps 41 that are bolted to the corners of the top plate 40, as at 41^a, suitable nuts 41^b being attached to the threaded upper ends of the posts 12. The top plate 40 is preferably a casting formed with ribs to give it the required strength and centrally through the top plate 40 is formed a pouring hole 42 through which the molten metal will be poured in the casting operation, as will presently more fully appear.

The underside of the top plate 40 is preferably formed with a recess within which is set the upper portion of the top mold section 45, this mold section being held rigidly to the top plate 40 by means of screws 46. This top mold section 45 is formed with a central opening 47 coinciding with the pouring opening 42 of the top plate, and the lower face 48 of the top mold section 45 is formed of the outline necessary to give the proper shape to the upper portion of the car wheel or other article to be cast. The lower

face of the top mold-section 45 is also formed with a rib 49 having an outer beveled edge and adapted to enter the correspondingly beveled seat 50 in a chilling ring 51, this chilling ring forming part of the central portion of the mold, and, in the apparatus shown, constituting the chiller for chilling the tread of the car wheel 52 to be cast. The under side of the ring 51 is formed with a beveled cavity 53 corresponding to the cavity 50 and adapted to receive the beveled guide rib 60 that rises from the upper face of the bottom mold-section 61.

The upper face of the bottom mold-section 61 is formed with suitable elevations 62 corresponding in outline to the shape of the article to be cast, these elevations 62 in a mold for car wheels serving to form the brackets or strengthening ribs on the sides 20 of the wheel. The bottom mold-section is formed with a central opening 62^a and, adjacent this central opening 62^a with a plurality of vertically disposed vent holes 63. These vent holes 63 have branch openings 64 near their upper ends leading into the central opening 62^a of the bottom mold-section, and the lower ends of the vent holes 63 communicate with an open space or chamber 65 formed at the bottom of the mold-section 61.

The lower portion of the bottom mold-section 61 is shown as seated within a recess formed in the vertically movable carrier or platen 70. This mold carrier 70 is preferably a casting having arms 71 projecting therefrom to the corner posts or standards 12. The outer ends of the arms 71 have concaved, babbitted portions 72 that serve as guides to slidably engage the posts 12. The bottom mold-section 61 is rigidly connected 40 to the mold carrier 70 by means of bolts 73 that pass through the mold-carrier 70 and into threaded openings in the lower portion of the bottom mold-section 61. The under-side of the mold carrier 70 is formed centrally with a hub 75 that is screw threaded to engage the upper end of the piston rod 17 which is adjustably secured thereto by means of a nut 17^a by which the mold carrier 70 is raised and lowered. Through the 45 mold carrier 70 are formed the vent holes 76 that communicate with the chamber 65 at the under side of the bottom mold-section 61 and through the mold-carrier 70 are formed three vertical openings 77 through 50 which loosely pass the rods 80 that are connected at their upper ends to the central support 81 that serves to sustain the central portion of the casting when the molds have been opened, as clearly shown in Fig. 2 of the drawings. The lower ends of the three rods 80 that depend from the support 81 are adapted to contact with the stops 30 that rise from the boss 25 of the cylinder head 16 (see Fig. 1).

From each side of the ring 51 that forms

the central portion of the mold, project studs 55 that carry at their ends anti-friction rollers 56 which, when the mold-sections have been opened, as shown in Fig. 2, contact with and rest upon the horizontal portions of the rails 57. These rails 57 are bolted to brackets 57^a secured adjustably on the corner posts or standards 12 and are supported centrally by upright bars 90, the lower ends of which are bolted, as at 91, to the base plate 11 and the upper ends of which are secured by angle bars 92 to the rails 57. The vertical bars 90 are preferably angle bars and are strengthened by strap irons 93 diagonally disposed and riveted to the angle bars 90.

In using my improved apparatus, as illustrated in the accompanying drawings, for the casting of car wheels, the parts will be brought to the closed position illustrated in Fig. 1 of the drawings, and at such time there will have been placed within the molds a central core 100 of dry or baked sand and a surrounding sand core 101 adapted to form the annular chamber around the hub of the finished wheel. Above the central core 100 will also have been placed a ring 102 of dry or baked sand, this ring having inwardly projecting legs that rest upon the conical upper part of the central core 100. The downwardly projecting portions of the annular core 101 rest upon the upper ends of the vent holes 63 and the lower portion of the central core 100 will rest upon the top of the support 81. In bringing the parts of the mold to the closed position shown in Fig. 1, it will be seen that the ribs 49 and 60 will insure the accurate alinement of the upper and lower mold sections and the chilling ring as the parts are brought together. With the parts of the mold thus closed and with the cores in position, metal will be poured through the opening 42 of the top plate and will pass down into the cavities formed by the mold sections. The vent holes 63 will permit the escape of gases passing from the sand cores through these vent holes to the chamber 65 and thence by the ports 76 to the atmosphere.

After the wheel 52 has been cast, the operator will shift the handle 24 of the three-way valve so as to cause air, steam or other fluid under pressure to be admitted to the upper portion of the cylinder 15 above the piston 18 and thus move down the carrier 70 and the bottom mold-section 61, and, as these parts move downward, the chilling ring 51, the wheel 52 and the support 81 will also move downward until the antifriction rollers 56 at the sides of the chilling ring 51 contact with the rails 57, at which time also the lower ends of the rods 80 below the support 81 will contact with the upper ends of the stops 30 that rise from the boss 25 of the cylinder head 16, and the mold carrier or

platens will contact with the stops 12^a secured adjustably by bolts to the posts or standards 12. The parts will then occupy the position shown in Fig. 2 of the drawings; 5 the support 81 serving to sustain the central portion of the freshly cast car wheel 52. The cast wheel 52 and the chilling ring 51 may then be moved away from between the top and bottom sections of the mold along 10 the tracks 57 to a point adjacent the annealing pit. As soon as the rim of the wheel is sufficiently chilled, it will shrink and will drop away from the chilling ring 51 and the wheel may then be annealed in the usual 15 manner, and the chilling ring 51 be returned to position between the top and bottom mold-sections. After a chilling ring has been returned to position between the top and bottom mold-sections, the cores will be placed in 20 position as above described, and the attendant will then shift the three-way valve so as to admit fluid under pressure to the lower end of the cylinder 15, thereby causing the mold carrier 70 and the lower mold section 25 to be raised until it lifts or picks up the chilling ring 51 and forces it upward against the under surface of the top mold-section 45, as shown in Fig. 1 of the drawings.

While I have described what I regard as 30 the preferred embodiment of my invention, I wish it understood that the details of construction and arrangement above set forth may be varied within wide limits without departing from the scope of the invention 35 and that features of the invention may be employed without its adoption as an entirety.

Having thus described my invention, what I claim as new, and desire to secure by Letters Patent, is:—

40 1. In a casting apparatus, the combination of separable mold-sections, an intermediate chiller movable toward one of the mold-sections, and means for shifting one of said mold-sections and said chiller simultaneously in the same direction and separating the same to open and close the mold. 45 2. In a casting apparatus, the combination of separable mold sections, a chilling ring interposed between said mold sections, and means for opening and closing the mold and for separating said chilling ring from both of said mold sections when the mold is open, to thereby permit the lateral movement of said chilling ring from between the mold sections.

50 3. In a casting apparatus, the combination of separable mold-sections, means for closing the mold, a chilling ring located between said mold-sections, said chilling ring being free to move laterally from between said mold-sections when the latter are separated and means for supporting said chilling ring during its lateral movement.

55 4. In a casting apparatus, the combination of separable mold-sections, means for

closing the mold, a laterally movable chiller located between said mold-sections and provided with projections or trunnions and rails or supports arranged at the sides of said chiller and whereon the chiller is sustained as it is moved away from the mold-sections.

5. In a casting apparatus, the combination of separable mold-sections, means for closing the mold, a laterally movable chiller 75 located between the mold-sections and provided at opposite sides with anti-friction rollers, and rails whereon said anti-friction rollers will travel as the chiller is moved away from the mold-sections.

6. In a casting apparatus, the combination of separable mold sections, a chilling ring arranged between and held in place by said mold sections when the mold is closed, and means for shifting one of said 85 mold sections to open the mold and for moving said chilling ring to a position clear of both of said mold sections to thereby permit the lateral movement of said ring from between the mold sections.

7. A casting apparatus comprising a frame, mold sections mounted thereon, a chilling ring held in place between said mold sections when the mold is closed, and means for opening the mold and for separating 95 said chilling ring from both of said mold sections to thereby permit the movement of said ring laterally from between said mold sections when the mold is open.

8. A casting apparatus comprising a frame, separable mold sections mounted thereon, a chiller held in place between said mold sections when the mold is closed, and means for opening the mold and for separating said chiller and the casting from 105 both of said mold sections to thereby permit the lateral movement of the chiller and casting from between said mold sections when the mold is open.

9. A casting apparatus comprising a frame, upper and lower mold sections mounted thereon, a chilling ring held in place between said upper and lower mold sections when the mold is closed, means for relatively shifting said mold sections and ring in vertical direction to open the mold and separate said chilling ring and the casting from said mold sections, to thereby permit the lateral removal of the chilling ring and casting from between said mold sections, and means for supporting said chilling ring during its lateral movement.

10. A casting apparatus comprising a frame, upper and lower mold sections mounted thereon, a chiller held in place between said upper and lower mold sections when the mold is closed, means for lowering said lower mold section and said chiller to open the mold and means for arresting said chiller and the casting in position clear of 130

- both of said mold sections to thereby permit the lateral removal of said chiller and the casting from between the same.
11. A casting apparatus comprising a frame, a fixed mold-section, a movable mold-section, a cylinder and piston for operating said movable mold-section, a chiller located between said mold-sections and movable toward and from the fixed mold-section and movable also laterally from between the mold-sections, when the latter are separated and means for supporting the chiller as it is moved from between the mold-sections.
12. A casting apparatus comprising a frame, a top mold-section at the upper part of said frame, a vertically movable mold-section beneath said top mold-section, a vertically and laterally movable chiller arranged between said mold-sections, and a cylinder and piston located beneath said movable mold-section for shifting said lower mold-section and the chiller to close the mold.
13. A casting apparatus comprising a frame, a fixed mold-section at the upper part of said frame, a vertically movable mold-section beneath said fixed mold-section, a vertically and laterally movable chiller arranged between said mold-sections, a cylinder and piston located beneath said movable mold-section for shifting the lower mold-section and the chiller, fluid delivery pipes leading to the opposite ends of said cylinder and valve mechanism for controlling the flow of fluid to said cylinder.
14. A casting apparatus comprising a frame, a top mold-section fixed at the upper part of said frame, a vertically movable mold-section beneath said top mold-section, a vertically and laterally movable chiller arranged between said mold-sections, vertical posts or guides for directing the movement of said movable mold-section, and a cylinder and piston located beneath said movable mold-section for shifting said lower mold-section and the chiller to close the mold.
15. A casting apparatus comprising a frame, a top plate at the upper part of said frame, a fixed mold-section secured to said top-plate, a lower movable mold-section, a support or platen for carrying said lower mold-section, guides for said support or platen, a cylinder and piston for shifting said lower mold-section and a vertically and laterally movable chiller arranged between said mold-sections.
16. A casting apparatus comprising a frame having a plurality of vertical posts, a top plate at the upper part of said frame, a fixed mold-section secured to said top plate, a lower mold-section, a support or platen for carrying said lower mold-section, arms projecting from said platen and engaging said posts of the frame to guide said platen in its movements, a cylinder and piston for shifting said lower mold-section and a vertically and laterally movable chiller arranged between said mold-sections.
17. A casting apparatus comprising a frame, a top mold-section at the upper part of said frame, a vertically movable mold-section located beneath said top mold-section and provided with a central opening, a vertically movable chiller arranged between said mold-sections, means for shifting said lower mold-section and said chiller, a vertically movable central support for the casting arranged to enter the central opening of the lower mold-section and means for limiting the downward movement of said central casting support.
18. A casting apparatus comprising a frame, a top mold-section at the upper part of said frame, a vertically movable mold-section located beneath said top mold-section and provided with a central opening, a vertically movable chiller arranged between said mold-sections, means for shifting said lower mold-section and said chiller, a vertically movable central support for the casting arranged to enter the central opening of the lower mold-section and means for limiting the downward movement of said central casting support, said means comprising rods depending from said support and adjustable devices for engaging the ends of said rods.
19. A casting apparatus comprising a frame, a top mold-section at the upper part of said frame, a vertically movable mold-section located beneath said top mold-section and provided with a central opening, a vertically movable chiller arranged between said mold-sections, a cylinder and piston for shifting said lower mold-section and said chiller and a central support for the casting movable with respect to the lower mold-section and arranged to set within the central opening thereof, when the mold is closed, and means for adjustably controlling the downward movement of said support.
20. A casting apparatus comprising a frame, a top mold-section at the upper part of said frame, a vertically movable mold-section beneath said top mold-section, a vertically movable platen for carrying said lower mold-section, said platen being provided with one or more vent openings and said lower mold-section being provided with a central opening and with vent openings extending vertically therethrough and having branch vent openings communicating with said central opening adjacent its upper end, a chiller located between said mold-sections, and a support for the central portion of the casting movable with respect to said lower mold-section and adapted to fit within the central opening thereof, said sup-

port being of less vertical dimension than the central opening of the lower mold-section to expose the inner ends of the vent ports to the sand core carried by said central support.

21. A casting apparatus comprising a frame, a top mold-section at the upper part of said frame, a vertically movable lower mold-section located beneath said top mold-section, a vertically movable chiller ar-

ranged between said mold-sections, means for shifting said lower mold-section and said chiller to close the mold, and means for limiting the downward movement of the chiller so that the lower mold-section may 15 be withdrawn from engagement therewith.
